United States Patent Office

Des. 188,086
Patented May 31, 1960

188,086

PURSE

Sarah R. Garcia, 268 W. Ash Ave., Burbank, Calif.

Filed Dec. 10, 1959, Ser. No. 58,625

Term of patent 14 years

(Cl. D87—3)

I claim:

The ornamental design for a purse, as shown.
